UNITED STATES PATENT OFFICE.

CHARLES EDWARD RICHARDS, OF BOONVILLE, NEW YORK.

SANDING APPARATUS FOR LOCOMOTIVES.

No. 911,158.

Specification of Letters Patent.

Patented Feb. 2, 1909.

Application filed November 5, 1906, Serial No. 341,972. Renewed December 14, 1908. Serial No. 467,539.

To all whom it may concern:

Be it known that I, CHARLES EDWARD RICHARDS, of Boonville, in the county of Oneida and State of New York, have invented certain new and useful Improvements in Sanding Apparatus for Locomotives; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my invention is to provide an improved sand box or sanding apparatus for locomotives or similar use, which is simple in construction, efficient in operation and in which provision is particularly made for overcoming or obviating any trouble from caked sand, and for the separation, discovery and removal of stones or matter which might obstruct the discharge openings and pipe.

Figure 1 shows a partial side elevation and a partial cross section of the device. Fig. 2 is a longitudinal sectional view of the device or apparatus. Fig. 3 shows details of a lock or catch for securing movable parts in fixed position.

Referring to the reference letters and figures in a more particular description, 1 indicates the casing which may be mounted on the top of a locomotive boiler, as 2, in any convenient manner. This casing is provided at the top with a removable cover 3 adapted to close a filling opening in the top. Within the casing there is mounted on journals or pivots 4—5 in a horizontal position a pair of sand receptacles 6—6, which are preferably of cylindrical form and are made intercommunicating by means of a slotted opening 5. Each receptacle 6 is provided with an opening having a removable cover 7, which is screw-threaded into closed position or otherwise suitably secured, and is adapted to come opposite the opening in the casing closed by the cover 3. The receptacles 6 are also each provided with a pair of discharge openings 8—8 adjacent to either end. Within the casing 1 there is provided a curved shield or bottom 9 in close proximity to which the sides of the receptacles 6 are adapted to swing when being revolved on the journals 4—5. At either end the shield or bottom 9 is provided with openings adapted to register with the openings 8 in the receptacle 6. For controlling these openings there are provided

gates or cut-offs consisting of a revolving core 10 mounted in a casing 11, and having transverse openings 12 adapted to register with said openings in the shield or bottom 9 and with the upper end of the pipes 13, which are extended, in the case of a locomotive, to points adjacent to the track directly in advance of the driving wheels. The openings in the shield and in the gates or cut-offs, as well as the passage through the pipe 13, are larger than the openings 8, so that anything that passes openings 8 will readily be passed and discharged by pipes 13.

For operating the gates or cut-offs there is provided on one end of the core 10 a lever 14, by means of which it may be rotated to a limited extent. In order to secure the sand receptacles 6 in a superimposed position, as shown in either Figs. 1 or 2, and provide for rotation thereof to permit them to be inverted, there is provided on one end of the casing 1 a sliding gravity catch 14 adapted to engage with a head 15 on the outer end of the journal 5, and this head 15 may also be arranged to receive a suitable wrench, by means of which the sand receptacles may be rotated within the casing when the catch 14 is disengaged by raising it upward a limited distance.

In rotating the sand receptacles some small portion might escape and pass through the openings 17 into the lower portion of the casing. In order to remove this the apparatus is supplied with one or more pipes as 16, by means of which a blast of compressed air, usually available on a locomotive, can be introduced in the casing to blow out or clean out the dust and sand from the lower portion, and the dust and sand being thus removed is adapted to pass out through openings 13^a into pipes 13. The casing also being made closed the pressure of air in the casing passing through the openings 13^a serves to clean out the pipes 13.

When the covers 3 and 7 are removed, the receptacles 6—6 may be more or less filled with sand, the sand from the upper receptacle finding its way into the lower one through the slot 5 until the lower one is full, the balance, if any, remaining in the upper receptacle. The sand may be discharged through the openings 9^a and conveyed by the pipes 13 to the rails when the gates or cut-offs are opened, and of course, when the gates are closed the flow will cease.

To determine whether the sand is in con-

dition to readily flow when the gates are opened, the catch 14 may be released and the receptacles 6 inverted. Then by removing the covers 3 and 7 it can be determined whether the contents of the upper receptacle is flowing properly into the lower receptacle, and if it is found to be so doing it will be known that the sand is not caked and the apparatus is in operative condition. If the sand is more or less caked the reversal of the receptacles 6, if the bottom one is not full, will break up and sufficiently agitate it to start it flowing. If the lower receptacle is full and caked upon reversal that fact will be ascertained and the same may be stirred until it starts to flow through slot 5 properly. The slot 5 will be made relatively narrow so that any stone or other obstruction which will not pass through the openings 8 will be caught and will be found in the upper receptacle and removed. As these receptacles are alternately on top these stones or obstructions are readily all discovered and removed, and can not for long obstruct a discharge opening.

What I claim as new and desire to secure by Letters Patent is:

1. The combination in a sanding apparatus for locomotives, etc., of a pair of reversible, intercommunicating sand receptacles, and means for discharging sand from the lower of said receptacles, substantially as set forth.

2. The combination in a sanding apparatus for locomotives, etc., of a pair of reversible, intercommunicating sand receptacles, openings for discharge of sand from the lower receptacle, and a gate controlling the flow of sand from said openings, substantially as set forth.

3. The combination in a sanding apparatus for locomotives, etc., of a pair of reversible, intercommunicating sand receptacles, means for mounting the receptacles for revo-

lution in reversing and securing them in operative position, openings from both receptacles adapted to afford passages for the flow of sand therefrom, and gates for controlling the flow of sand, substantially as set forth.

4. The combination in a sanding apparatus for locomotives, etc., of a pair of reversible, intercommunicating sand receptacles mounted on journals, a casing inclosing said receptacles and having a concave bottom adjacent to which the lower receptacle is adapted to take position, sand discharge openings in said receptacles, openings in said shield coincident with those of the receptacles, and a cut-off controlling the openings from the shield, substantially as set forth.

5. The combination in a sanding apparatus for locomotives, etc., of an inclosing casing having a concave bottom or shield free at either edge with reference to the casing, a two - part reversible, intercommunicating sand receptacle mounted above the shield, and passages for withdrawing sand through said shield, and cut-offs controlling the passages through the shield, and means for supplying air under pressure within said casing, substantially as set forth.

6. The combination in a sanding apparatus for locomotives, etc., of a closed casing having a movable sand receptacle located therein, a discharge pipe leading from said receptacle and a gate controlling the flow thereto, an opening into said pipe from the lower part of the casing, and means for supplying air under pressure to the casing, substantially as set forth.

In witness whereof, I have affixed my signature, in presence of two witnesses, this 29 day of Oct. 1906.

CHARLES EDWARD RICHARDS.
